UNITED STATES PATENT OFFICE

LEONTINE GERALDINE, OF SAN FRANCISCO, CALIFORNIA

POMPON

Application filed January 26, 1931. Serial No. 511,427.

My present invention relates to improvements in pompons or ornamental devices used for various purposes, but particularly employed in interior decorating in connection with furnishings, curtains, draperies, portieres, or drapes for windows, doors and similar structures. The primary object of the invention is the provision of an article of manufacture, which in addition to being ornamental, also performs the functions, in combination with a tie strap, of holding or retaining the gathered folds of the draperies. The pompon is constructed in such manner and provided with means whereby the pompon assists in forming one of the folds of the draperies and retains the fold as well as the other gathered folds in proper adjusted position within the tie strap.

Suitable means are provided whereby the pompon joins and fastens the ends of the tie strap which is used in the formation of a loop around the gathered folds of the draperies. While I have shown in the drawings only one of the pompons employed at one side of a window or door, it will be understood that the tie straps and pompons are utilized in pairs, and it will also be apparent that the pompons may be fashioned in various sizes and shapes.

The dimensions and relative proportions of the different parts of the ornamental device may be varied; different contrasting colors and different materials may be utilized in the arrangement of the parts of the pompon, but of course the colors used will be in harmony with the color scheme of the draperies with which the pompons are employed.

The invention consists essentially in certain combinations and arrangements of parts employed in the structure of the pompon whereby a structure that is durable as well as ornamental is insured, and in which the different parts of the pompon are secured together, as a whole, to prevent displacement of parts as well as to prevent the pompon from becoming misshapen. Due to the simple arrangement of parts and the minimum number of parts employed in the structure of the pompon the latter may be manu-

factured with facility and at comparatively inexpensive cost of production.

In the accompanying drawings I have illustrated one complete example of the physical embodiment of my invention wherein the parts are combined and arranged according to one mode I have devised for the practical application of the principles of my invention, but it will be understood that various changes and alterations are contemplated within the scope of my claims without departing from the principles of my invention.

Figure 1 is a view showing a portion of one half of the drapes for decorating the interior of a door or window, and illustrating the use of the pompon.

Figure 2 is a conventionalized face view of a pompon according to my invention.

Figure 3 is a transverse sectional view, also conventionalized, of the pompon, and Figure 4 is an exaggerated view of a portion of the braid employed in the structure of the pompon.

Because of the limitations in the patent drawings, the illustrations are necessarily mechanical or conventional, rather than ornamental, but it will be apparent that artistic and tasteful effects and attractive appearances may readily be attained in the physical embodiment of the pompon, which effects and appearances could not be produced in the black lines of the drawings.

In order that the general assembly and relation of parts may readily be understood I have indicated in Figure 1 a portion of the drapery 1 arranged in folds 2, and the tie strap 3 is formed in a loop to hold the gathered folds of the drapery. The tie strap here shown is of plaited formation, but it will be apparent that other forms of straps or ropes may be employed and fashioned from suitable materials in tastefully arranged colors to harmonize with the color scheme of the drapes.

The pompon is indicated as a whole by the numeral 4 and it is permanently attached to one end of the tie strap. On the back of the pompon a suitable hook, as 5 or other desirable fastening device, is stitched, and this fastening device co-acts with a complementary 100

fastening member attached to the other end of the tie strap.

The pompon 4 is built or fashioned on a base or core 6, preferably made of wood, and as here shown the base is a circular disk having a convex front face for use in shaping the pompon. The core or wood base is covered with a suitable fabric as 7, and this cover or casing is employed as the anchoring member to which the parts of the pompon are secured 10 with invisible stitches.

Around the outer edge of the circular core 6 a fringe of fibrous, fluffy material, as silk, is secured, this fringe or trimming being fashioned from a strip of braid 8 in Figure 15 4, and the edge 9 of the strip is formed of loose, smooth, fluffy fibers of the braid. The strip of braid, in circular shape, is stitched at its inner edge to the casing or cover of the core with the body of the braid flat against 20 the core, while the loose fibers radiate outwardly from the core in a fluffy mass, for ornamental purposes.

The inner edge of the circular strip of braid which lies flat against and is stitched 25 to the casing of the core, and a portion of the face of the core, are covered with an ornamental mat, in the form of a coil of silk cord 10, which forms the face of the pompon, and this cord or rope in concentric circles, or 30 in a spiral coil, is securely stitched together, and also securely stitched to the casing 7. The silk cord or rope is preferably formed with strands, which may vary in contrasting 35 colors, and of course they harmonize with the other colors of the pompon and with the colors of the drapery.

At the center of the pompon a puff is fashioned, which may be of the same texture as the fringe or trimming 9 at the outer edge 40 of the pompon. The puff is fashioned from a strip of braid, as indicated in Figure 4, and the braid is coiled into a solid knot as 11 from which the fluffy fibers radiate to form 45 of the puff 12. The puff is secured to the central part of the pompon and is firmly attached, as by stitching the knot 11 to the casing 7 of the core.

At the back of the pompon, and invisible 50 from the front, a knob 13 is attached, for use in forming a fold at the back of the pompon, as indicated by dotted lines in Figure 3. The knob may be of any suitable material, as wood, and while here shown as 55 of spherical form or shape, may be of any other suitable shape. The wood knob is transversely bored, as at 14, and a screw 15 is employed to secure the knob to the core of the pompon. The bore forms a socket for 60 the insertion and guidance of a screw driver when used for fastening the knob by the screw to the pompon. As indicated in Figure 3 the knob is of sufficient size and suitable shape to cause the drapery to hang with a fold, and the knob retains this fold as a

guide, for adjusting the other folds gathered in the tie strap.

Having thus fully described my invention, what I claim as new and desire to secure by Letters Patent is:—

1. An ornamental device of the type described comprising a rigid core and its cover, a fringe-member having its body secured to the cover and a fluffy fibrous portion of said member projecting beyond the periphery of the core, a mat within the fringe-member and secured to the cover, and a central puff within the periphery of the mat.

2. An ornamental device of the type described comprising a central core having a fabric cover, a fringe-member comprising a strip of braid secured at the outer edge of the core and provided with a fluffy fibrous edge, a coil of rope forming a mat and secured to said cover within the fluffy edge, and a central puff secured to said cover, said puff comprising a knot formed of braid and having loose fluffy fibers radiating therefrom.

3. The combination with a pompon including its rigid core, of a fold-forming knob at the back of the pompon, and means for attaching said knob to the core.

4. In an ornamental device for use with the tie-strap for drapes, the combination with a pompon and means for fastening the ends of said strap, of a fold-forming spherical knob at the back of the pompon, said knob having a tool socket therein and a screw for fastening the knob to the core.

In testimony whereof I have affixed my signature.
